UNITED STATES PATENT OFFICE.

WILLIAM WEBSTER WILSON, OF LOS ANGELES, CALIFORNIA.

HOISTING TACKLE.

Application filed July 24, 1923. Serial No. 653,586.

This invention relates most particularly to well drilling apparatus and to hoisting tackle for handling casing, pipe, and drill pipe or drill stem. Although it is, as will be understood from the device itself, adapted for use generally in connection with handling well pipe and casing, the particular form of the device herein illustrated and hereinafter described in detail has been designed with a view to expeditiously and safely handle a drill pipe and drill stem in rotary drilling rigs. So in the following specification, but without limiting my invention to this particular use, I shall describe the invention as it is used for handling drill pipe in a rotary drilling rig.

Heretofore it has been common to handle such drill pipe with an elevator having a bail or a pair of bails, and with a hoisting tackle that has a hook engaging the bails.

After the drill pipe is lowered in the well and if it becomes necessary to add a new length, the elevator previously in use is left standing on a support at the floor, the hook is disengaged and then engaged in the bail or bails of a second elevator in which the next length is held. The swivel water connection to the upper end of the previous length is disconnected and connected to the top end of the next length, the next length is screwed into the upper end of the previous length, and then the elevator below is disengaged and the drilling operation and the lowering of the pipe is resumed. In these operations the time element is of very great importance as it is essential in rotary drilling operations to keep the water flow as nearly continuous as possible. The disengagement and engagement of the hook are usually rather awkward operations and at times somewhat dangerous. Furthermore, the hooks although constructed very heavily, occasionally fail and sometimes with disastrous results.

It is a general object of the invention to provide a device to take the place of the hook in such hoisting tackle, and that this be quickly and easily disconnected from or connected to an elevator, and that is of comparatively light weight and yet strong and safe. Other objects of the invention will be best understood from the following detailed description reference for this purpose being had to the accompanying drawings in which—

Fig. 1 is a view partly in elevation and partly in central vertical section; Fig. 2 is a side elevation of the device; Fig. 4 is a horizontal section on line 3—3 of Fig. 1; Fig. 3 is a similar section showing the elevator halves opened out; Fig. 5 is an elevation showing a modified form; and Fig. 6 is a side elevation of the same.

In the drawings I show, in my complete combination, a pipe elevator E of the general design and with appurtenances such as shown in the patent of E. C. Wilson, No. 1,498,141, granted June 17, 1924, on Well elevators and in the patent of Charles E. Wilcox, No. 1,511,699, granted October 14, 1924, on Well pipe elevators.

However, except in some particulars as will be understood from the following statements the particular type of elevator used here is of no special consequence. This type of elevator has two bail lugs 10 on its opposite hinged halves and the two bails 11 are in the form of links and their lower ends passed through openings 12 in the bail lugs. These openings 12 have diagonal slots 13, so placed and of such size that if the bails are laid down toward a horizontal position (both in the same direction—the two slots here being parallel) then they may be easily disengaged from the elevator by slipping one of their straight sides out through slots 13. In their normal upright positions the bails cannot be disengaged as their curved lower ends will not pass through slots 13. How this is accomplished will be easily understood from the drawings. I here make no claim to this feature of itself, but only in combination with other features herein described. I also show the lugs 10 curved as is particularly described in my Patent No. 1,468,589, granted September 18, 1923, entitled Elevators. Such formation of the lugs allows the elevator halves to be swung open on their hinge 15 without swinging or twisting the bails 11 about a vertical axis and thus enables the elevator halves to be opened while the upper ends of the bails are in engagement with swivel S. The details of this arrangement need not however, be gone into here as such structure is the subject matter of my said patent. Figs. 3 and 4 show elevator halves in closed and open position and show how the bails swing outwardly at their lower ends without twisting about a vertical axis and thus show how the bails may remain

in engagement with the relatively small bail receiving openings of the swivel while the elevator is being opened and closed. This is of some decided advantage, and it is also advantageous to have the upper ends of the bails fit through the swivel lugs comparatively closely (instead of being in a large loose opening or instead of being merely hooked into a hook) and the structure or elevator which I here describe allows of these advantages and at the same time allows the elevator to be easily opened and closed.

Swivel S is the part that takes the place of the ordinarily used hook. This swivel has an eye bolt 30 carrying a ball race 31 and the body 32 of the swivel is directly supported by a spring 33 which is carried on the upper ball race 34. Body 32 has bail lugs 35 with bail receiving openings 36 just slightly larger than the bails so that the bails are held not tightly but yet comparatively snugly and without any great looseness. These bail receiving openings may be constructed in the same manner as before explained in connection with elevator E; that is, they may have diagonal slots through which the bails may easily be disengaged from the lugs; or the bail removal slots 37 may have closure blocks 38 that may normally be held in place by bolts 39. It is the particular object in this specific part of the construction as well as in the connection of the bails to the elevator, to provide that the bails shall be securely held but at the same time shall be quickly and easily removable. I may also mention here that it is not absolutely necessary for the bails to be removable from both the elevator and the swivel; easy removability from either may answer ordinarily the purposes for which the device is intended; but it may be desirable in some instances to have the bails removable from both as it may sometimes be desirable in operation to disengage the bails from the elevator and then at other times to disengage them from the swivel.

In Fig. 5 I show the elevator having a removable block 13^a to close slot 13 leading to the opening 12 through which bail 11 passes. In this form the bails are easily removed by removing block 13^a and then moving the lower ends of the bails downwardly and outwardly, it not being necessary to move the bails to diagonal position, as in Fig. 2, for removal and in this form the blocks might be omitted, the bails being normally held in engagement with the elevator by pulling up into openings 12 behind overhanging wall 12^a. In this form the lugs 10 may also be curved to attain the action illustrated in Figs. 3 and 4.

It is unnecessary for me to point out how and why this construction is particularly strong, safe and reliable, as it can be readily

understood from the drawings that 198 swivel structure is a great deal stronger than any hook of the same weight. In using my tackle, when it is desired to couple up a new length of drill pipe, the bails may be disengaged either from the elevator or from the swivel and then the swivel and bails, or the swivel alone, may be moved over and engaged with the other elevator. It may be preferable in operation to always disengage the bails from the elevator—to always keep the bails with the swivel—as the bails are then out of the way, as regards the elevator standing on the floor and supporting the pipe in the well, and also because then one set of bails suffices. It will be readily understood that the bails may be interconnected very quickly and without any trouble. When the device is in use, the spring 33 absorbs all shocks and eases off strains on the pipe, hoisting tackle, line, derrick and hoisting apparatus.

Having described a preferred form of my invention, I claim:

1. In combination, a pipe elevator with link receiving lugs, a connector comprising a stem having means at its upper end for connection with a tackle block, a yoke disposed rotatably about said stem and having laterally extending lugs provided with link receiving portions, means on the lower portion of the stem for sustaining said yoke, and links extending between and engaging the elevator lugs and the yoke lugs.

2. In combination, a pipe elevator with two opposite link receiving lugs, a connector comprising a stem having means at its upper end for connection with a tackle block, a yoke disposed rotatably and longitudinally movable about said stem and having two opposite laterally extending lugs provided with link receiving portions, resilient means supported on the lower portion of the stem for sustaining said yoke, and a pair of links extending between and engaging the yoke lugs and the elevator lugs.

3. In combination, a pipe elevator with link receiving lugs, a connector comprising a stem having means at its upper end for connection with a tackle block, a yoke disposed rotatably about said stem and having laterally extending lugs provided with link receiving portions, means on the lower portion of the stem for sustaining said yoke, and links extending between and engaging the elevator lugs and the yoke lugs, said links being removable from the elevator lugs.

4. In combination, a pipe elevator with two opposite link receiving lugs, a connector comprising a stem having means at its upper end for connection with a tackle block, a yoke disposed rotatably and longitudinally movable about said stem and having two opposite laterally extending lugs provided with link receiving portions, resilient means sup-

- ported on the lower portion of the stem for sustaining said yoke, and a pair of links extending between and engaging the yoke lugs and the elevator lugs, said links being removable from the elevator lugs. 35
5. A block and elevator connector, comprising a cylindrical stem having a head and eye at the upper portion thereof, a yoke disposed rotatably about said stem and having laterally extending lugs provided with link-receiving grooves, and means on the lower portion of the stem for sustaining said yoke. 10
6. A block and elevator connector, comprising a cylindrical stem having means at its upper end for connection with a tackle-block, a yoke fitting rotatably about said stem, said yoke having opposite laterally extending lugs provided at the upper sides thereof with link-receiving grooves, means 15 on the lower portion of the stem for sustaining said yoke, and means for retaining elevator-links in said grooves of the yoke-lugs. 20
7. A block and elevator connector, comprising a cylindrical stem, a yoke slidably and rotatably disposed upon said stem, said yoke having opposite laterally extending lugs adapted for engagement by elevator links, means at the upper end of the stem for connecting the same with a tackle-block, a 25 spring disposed about the lower portion of the stem and yieldably supporting the yoke 30
- thereon, and means at the lower end of the stem for supporting said spring. 35
8. A block and elevator connector, comprising a stem having means at its upper end for connection with a tackle block, a yoke disposed rotatably about said stem and having laterally extending lugs provided with link receiving portions, and means on the lower portion of the stem for sustaining said yoke. 40
9. A block and elevator connector, comprising a stem having means at its upper end for connection with a tackle block, a yoke 45 disposed rotatably about said stem and having oppositely laterally extending lugs provided with link receiving portions, and means on the lower portion of the stem for sustaining said yoke. 50
10. A block and elevator connector, comprising a stem having means at its upper end for connection with a tackle block, a yoke disposed about said stem and movable rotatably and longitudinally thereof and having laterally extending lugs provided with link receiving portions, and resilient means supported on the lower portion of said stem for resiliently sustaining said yoke. 55

In witness that I claim the foregoing I 60 have hereunto subscribed my name this 14th day of July, 1923.

WILLIAM WEBSTER WILSON.
